DESIGN FOR A CASING FOR METALWORK- ING MACHINE

Guy C. Worrell, Westfield, Mass.

Application October 19, 1937, Serial No. 72,318

Term of patent 14 years

To all whom it may concern:

Be it known that I, Guy C. Worrell, a citizen of the United States, residing at Westfield, in the county of Hampden and State of Massachusetts, have invented a new, original, and ornamental Design for a Casing for Metalworking Machine, of which the following is a specification, reference being had to the accompanying drawings, forming part thereof.

Fig. 1 is a side elevational view of a casing for metalworking machine showing my new design;

Fig. 2 is an end elevational view of the same; and

Fig. 3 is a small-scale plan view of the same.

I claim:

The ornamental design for a casing for metalworking machine, as shown.

GUY C. WORRELL.
